WALL AND CEILING BOARD CLIP

Filed Feb. 7, 1928

UNITED STATES PATENT OFFICE

CALVIN CAMPBELL, OF DENVER, COLORADO, ASSIGNOR TO THE COLORADO FUEL AND IRON COMPANY, OF DENVER, COLORADO, A CORPORATION OF COLORADO

WALL AND CEILING BOARD CLIP

Application filed February 7, 1928. Serial No. 252,532.

This invention relates to fastenings for composition boards of the kind used in the construction of walls and ceilings of buildings and other structures and its primary object is to provide a clip of simple construction which is readily applied and which provides a safe, reliable and rigid means for fastening wall or ceiling board to metal studs, joists and other flanged structural supports.

A further object is to provide a clip of the above described character which is made of a single piece of bendable metal with or without a rust proof coating.

Another object resides in providing a clip for fastening wall or ceiling boards that can be applied to one or both sides of a flanged structural support.

A further object is to provide a clip adapted for fastening wall or ceiling boards at a definite distance from an edge of the structural support or flush with said edge in accordance with different positions of the boards with relation to the supports.

Another object is to provide a clip applicable to flanged supports of different widths; and still further objects reside in details of construction as will be fully described in the course of the following description.

An embodiment of the invention has been illustrated in the accompanying drawings in which like characters of reference designate corresponding parts throughout the views, and in which,

Figure 1, represents a perspective view of the clip;

Figure 2, a face view of ceiling-boards adjoining one another at a distance from an edge of a flanged support and fastened together and to the support, by means of the clip;

Figure 3, a section taken on the line 3—3, Figure 2;

Figure 4, a section similar to Figure 3, showing the method of applying the clip to a board flush with a face of the flanged support; and

Figure 5, a section on the line 5—5, Figure 4.

Referring further to the drawings, the clip as illustrated in Figure 1, comprises a single

length of sheet metal bent to provide a body-member 5 and end-members 6 at right angles thereto. The three members are cut and portions thereof bent at right angles to provide two pairs of arms 7 at opposite ends of the body-member, flanges 8 projecting outwardly from the end-members and flanges 9 extending in the planes of the end-members.

The arms 7 and the flanges 8 are formed by two parallel slits in the end members, and the flanges 9 are formed by U-shaped cuts in the end-portions of the body-member.

The flanges 8 are partially split as at 10, to provide tongues 12 which in practice are bent along lines 13 that may be defined by perforations or other weakening means; and the flanges 9 have similar rows of perforations 14 defining tongues 15.

Now referring to Figures 2 and 3 of the drawings, the reference character 16 designates a joist, stud or other structural support made of flanged metal. The support as shown, is of channel section, and has two flanges 17 at the ends of a body-plate, but it is to be understood that the clips may be applied as well to supports of different forms.

Wall or ceiling boards 18 resting against the flanges of the support meet at a distance from the edges of the same and they are secured at their abutting ends to each other and to the flanges of the support by means of the hereinbefore described clips in the following manner:

The body-member of the clip is placed flat against the body-plate of the support and the arms at opposite ends thereof are bent around the outer edges of the flanges. The flanges 9 of the clip extending in the planes of the arms, rest against the inner surfaces of one of the boards at each side of the support, the flanges 8 between the arms, extend between the abutting ends of the boards, and the tongues 12 at the ends of the flanges, defined by the weakened lines, are bent in opposite directions upon the outer surfaces of the boards.

The weakened bending lines of the last mentioned flanges are at a distance from the respective end-members of the clip, slightly less than the average thickness of wall or

ceiling boards so that when the tongues defined by the lines are bent at right angles upon the outer surfaces of the boards, they may be pressed into the material of which the boards are composed so as to lie flush with the outer surfaces of the same. Thus, the clips may be completely concealed by a filler or filler-strips used in finishing the structure of which the boards are a part.

The application of the tongues in the manner shown and described, furthermore draws the boards tightly against the flanges of the support and the clips secure the boards permanently in alinement and fasten them firmly and permanently to each other and to the structural supports.

Figures 4 and 5 of the drawings, illustrate the method of applying the clips to wall or ceiling boards 19 extending to an edge of the support, as, for example, in places where an adjoining board 20 lies flush against the face of the body-plate of the support.

The flanges 9 which in the fastening method illustrated in Figures 2 and 3, served merely as an additional support for the boards, now function to secure the boards resting against the flanges, and the flanges 8 which in the first described form, were the fastening means, are bent into the planes of the arms which as before are bent across the outer edges of the flanges. The flanges 9 embrace their ends of the boards resting against the flanges of the support and the tongues 15 are bent upon the outer surfaces of the boards.

The bending lines are again formed at a distance from the members of the clip, slightly less than the thickness of wall or ceiling boards so that the tongues may be pressed into the material of the boards and the ends of the boards may be flush against the cross-board engaging the body plate of the structural support.

It will be apparent that the clips formed as shown and described may be applied in different manners for fastening wall and ceiling boards to each other and to their supports, that by means of the clips the boards may be secured at one side of a support only or simultaneously at both sides of the same, as the case may be, or that by application of one and the same clip, wall boards ending at a distance from an edge of the support, as in Figure 3, may be fastened at one side of the support and a wall board extending to the edge of the support, as in Figure 4, may be secured at the opposite side of the support.

The clips may be made of any suitable bendable metal and they may be coated with a rust proof substance if so desired.

It will further be seen, that owing to the provision of the bendable arms, the clips may be applied to structural supports, irrespective of the shape or of the width thereof.

What I claim and desire to secure by Letters Patent is:

1. A clip of the character described comprising a body-member, a bendable arm at an end thereof, and a flange projecting outwardly from the arm, the flange having bendable tongues formed by a slit in the end-portion of the same. 10

2. A clip of the character described comprising a body-member, bendable arms at an angle to the body-member at opposite ends thereof, bendable flanges projecting outwardly from the arms, and bendable flanges projecting from the body-member, opposite to the arms. 75 80

3. A clip of the character described formed of a single length of metal, into a body-member and an end-member at an angle to the body-member, bendable arms formed by slits in the end-member, an outwardly projecting flange formed of the portion of the end-member between the slits, and a flange extending opposite to the end-member and formed by a cut in the body-member. 85

4. A clip of the character described formed of a single length of metal, into a body-member and end-members at an angle to the body-member, bendable arms formed by slits in the end-members, outwardly projecting bendable flanges formed by the portions between the slits, and flanges extending opposite to the end-members, formed by cuts in the body-member. 90 95

5. A clip of the character described comprising a body-member, end-members bent at an angle thereto and divided by slits to form bendable arms and flanges, and flanges formed by bent-out portions defined by U-shaped cuts in the body-member adjacent the end-members. 100 105

6. A clip of the character described having bendable arms to embrace a structural support and a flange having a weakened line and a slit conjointly defining tongues to embrace wall boards of given thickness resting against the support. 110

7. A clip comprising a body-portion, an arm at an angle to the body portion, bendable to embrace a flange at an end of a structural support, and a flange projecting outwardly at substantially right angles to the arm, and bendable to embrace an end of a wall board placed against the arm and across the flanged end of the support. 115 120

8. A clip comprising a body-portion, an arm at an angle to the body portion, bendable to embrace a flange at an end of a structural support, and flanges bendable to project at substantially right angles to the arm, and having their ends bendable to embrace a wall board placed against the arm and across the flanged end of the support, one of the flanges being at the end of the arm at which it adjoins the body portion and an- 125 130

other flange being at a point between the ends of the arm.

9. A clip comprising a body-portion, an arm at an angle to the body portion, bendable to embrace a flange at an end of a structural support, and a flange projecting outwardly at substantially right angles to the arm at the end thereof at which it adjoins the body-portion, and bendable to embrace an end of a wall board placed against the arm and across the flanged end of the support.

10. A clip comprising a body-portion, an arm at an angle to the body portion, bendable to embrace a flange at an end of a structural support, and a flange projecting outwardly at substantially right angles to the arm between the ends thereof, and bendable to embrace an end of a wall board placed against the arm and across the flanged end of the support.

In testimony whereof I have affixed my signature.

CALVIN CAMPBELL.
